DEVICE FOR FORMING ANNULAR GROOVES

Alfred Rickenmann, Zurich, Switzerland; vested
in the Alien Property CustodianApplication December 16, 1941, Serial No. 423,224
In Switzerland November 12, 1940

4 Claims. (Cl. 51—72)

The invention relates to a new and improved device for accurately forming annular grooves and ridges on a cylindrical workpiece such as is intended for turning grinding wheels for use in correcting screw threads and so on.

The invention relates more particularly to a device in which during a complete revolution of the cylindrical workpiece the latter is moved axially relative to the grinding disk by cams against the action of a spring a distance equal and opposite to the extent to which the grinding wheel is axially fed so that actually the grinding disk remains stationary in space while one of the annular grooves is being formed by said grinding disk. After one revolution of the cylindrical workpiece the said cams and the said spring effect a relative axial displacement of the grinding disk with reference to the cylindrical workpiece the said relative displacement is equal to the distance between the annular grooves.

The main object of the invention consists in the provision of improved means to cross feed the grinding disk with reference to the cylindrical workpiece after an annular groove has been completed and before the formation of an adjacent one is being started.

The invention will be better understood by reference to the following description in conjunction with the accompanying drawings.

In the accompanying drawings the preferred embodiment of the invention is shown in a diagrammatical manner.

Fig. 1 is a side elevation and

Fig. 2 a front elevation of the new grinding machine

Fig. 3 is a section taken on line III—III of Fig. 2 parts

Fig. 4 is a section on the line IV—IV of Fig. 3

Fig. 5 illustrates the section of the cross feeding device by a cam.

In the base A a headstock B, a tailstock C and a cross slide D are slidably and adjustably mounted on the ways E in the usual manner. In the base A a horizontal shaft 2 is journaled. The shaft 2 is driven from a motor shaft 1 by means of the spur wheels 40, 41. The shaft 2 is provided with an extension 2¹ having key 43 and on this extension 2¹ a spur wheel 3 is slidably arranged meshing with a spur wheel 4 loosely mounted on a shaft 5 of the headstock B. The gear 3 is secured against axial displacement by a bearing 17 mounted on a screw-threaded spindle 15. The latter is journaled in the base A and is driven by a set of spur wheels 16. On a key of the shaft 5 a sleeve 6 is slidably mounted.

5 A tooth on one face of the sleeve 6 may be brought in and out of engagement with a notch on the spur wheel 4. In the shaft 5 a second shaft 7 is rotatably mounted carrying on the one end a cam disk 10 and on the other end a spur wheel 44 meshing with a toothed rim 8 of a sleeve 45. The said sleeve 45 is rotatably mounted on a shaft 46 and meshes with a toothed rim 47 with the teeth 48 of the shaft 5. The shaft 7 is slidably arranged, a coiled spring 9 tends to press the said cam 10 on to a corresponding camplate 11 rigidly connected to the shaft 5. The workpiece 12 is held between the point 7¹ of the shaft 7 and point 13 slidably arranged in a bore of the tailstock C. The point 13 rests on a spring 14 which is compressed when the shaft 7 with the workpiece 12 is moved in axial direction. The workpiece 12 takes part of the rotation of the cam disk 10, a dog 49 fixed on said cam disk 10 engages a radial arm 50 attached to the workpiece 12.

10 The spur wheel 41 of shaft 2 meshes with a spur wheel 52 rotatably mounted in the base A. The wheel 52 drives by two universal joints 53 and 54 and rod 31 a steering shaft 18 journaled in the base A. On shaft 18 a cam 25 is keyed co-operating with a follower 24 of a double armed lever 24 mounted in the base A. The lever 24 actuates a shaft 21 by its free end 21¹. The shaft 21 is axially slideable and rotatably mounted in the base A. A screw threaded portion 55 of the spindle 21 engages a nut 29 forming part with the casing 19 of the cross slide D. In the casing 19 the grinding disk S is journaled adapted to work on the piece 12. A spring 20 abutting with one end on base A and with the other tends to withdraw the grinding disk S from the workpiece 12. On the spindle 21 a piston 22 is fastened which is slidably mounted in a cylinder 23.

15 The space behind the piston 22 is connected by a pipe 27 to the casing 57 of a distributing valve 58. In the casing 57 a piston 59 fixed on shaft 18 is arranged having grooves to interconnect the port of pipe 27 with either the port of a pipe 26 or with the port of the exhaust pipe 30. By turning the valve piston 59 fluid under pressure may be forced into cylinder 23 or may be allowed to flow off, causing an axial displacement of the spindle 21 and of the cross slide D. The cross slide D may be fed by means of the shaft 28 and two spur wheels 35, 36 and the screw threaded portion 55 of the lead screw 21 and nut 29. The shaft 28 may be turned by a hand wheel to bring the cross slide D to and from the workpiece 12.

20 The arrangement of the parts is such that

during a complete revolution of the shaft 5 and the workpiece 12 the latter is moved axially by the cams 10, 11 against the pressure of the spring 14 a distance equal t Fig. 3 and opposite to the extent t to which the shaft 5 and the headstock B are fed so that actually the grinding disk 11 remains stationary in space while one of the annular ridges is being formed. The ratio of rotation between the shafts 5 and 7 is 1 to 2, the shaft 7 makes two revolutions while shaft 5 makes but one. If shaft 1 is rotated in the direction of the arrow the carriage B is moved for a distance equal to t the distance between two adjacent annular ridges in the workpiece 12. As the speed at which the two shafts 5 and 7 run is different, the axial displacement of the workpiece 12 and of the carriage B takes place as described above for a like amount but in opposite direction. As soon as the workpiece 12 has completed a full revolution the grinding disk S is withdrawn from the workpiece by the cam 25. The shaft 5 and 18 run at the same speed. The piston valve 59 is such that shortly before the follower 10 passes over the step incline 11¹ of cam 11 the pressure pipe is closed while at the same time the pipe 27 is connected with the flow-off pipe 30. The grinding disk S is withdrawn from the workpiece 12 shortly before the same has been shifted for the distance t by the springs 9 and 14. The latter therefore shift the shaft 1 to the left Fig. 3, while the follower 10 passes over the incline 11¹. To start the withdrawal of the grinding disk S from the workpiece the follower 24¹ passes over the zone $a-b$ of the cam 25 (Fig. 5). The grinding disk S leaves the workpiece by slow degrees. After the axial displacement of the workpiece 12 has taken place the valve 59 allows liquid under pressure to enter the space 23. The piston 22 starts to feed the grinding disk S on to the workpiece while the follower 24¹ passes over the point c of the cam 25. The feeding-in occurs gradually until the follower 24¹ passes over the point d . The gradient of the slopes a to b and c to d is low to prevent any jerky movement of the slide D. While the follower 24¹ passes from point d to point a the workpiece 12 makes at least one full turn. During this time the disk S remains in its working position.

After all the annular grooves have been formed, the grinding disk S is returned to its

initial position. To attain this the clutch member 6 is moved to the left Fig. 3 and the space 23 is brought to communicate with the off-flow pipe 30. The workpiece 12 remains thereby stationary and the disk S is kept off the workpiece. The clutch member 6 has but one tooth and the co-operating gear 4 but one notch to receive said tooth, therefore the parts assume automatically the correct relative position to ensure a correct setting of the disk S with reference to the groove pre-formed to allow a second cut.

What I wish to claim and secure by U. S. Letters Patent is:

1. A device for accurately forming annular grooves and ridges on a cylindrical workpiece of the type described comprising in combination a grinding disk, means for rotating and for axially feeding the workpiece, rotatable cam means for effecting continuous axial feeding between the said grinding disk and the workpiece at the rate of one groove of the workpiece for at least one complete revolution thereof, means for holding the grinding disk and the workpiece axially relatively to one another during a complete revolution, so that during the said whole revolution the grinding disk and the workpiece remain axially stationary relatively to one another, spring means independent of said cam means for effecting an axial return movement of the workpiece relatively to the grinding disk for a distance equal to the said advance feeding means for permanently constraining said grinding disc to a cross-feed movement away from the work, and means for controlling said permanently acting means to cross-feed said disc at the end of one complete revolution of said work piece away from and towards the work piece.
2. A device as defined in claim 1 in which the control means to cross-feed the grinding disk are operated automatically.
3. A device as defined in claim 1 in which the control means to cross-feed the grinding disk are operated automatically, said means comprising a positively driven cam actuated in predetermined relation to the movement of the work piece.
4. A device as defined in claim 1 in which the control means to cross-feed the grinding disk are operated automatically, said means comprising a hydraulic device positively operated by the gearing which rotates the working piece.

ALFRED RICKENMANN.
